JACK LEG PULLEY

Allan De Wolf, Ferndale, Mich., assignor, by direct
and mesne assignments, to Walter C. Clevenger,
Royal Oak, Mich.

Application July 1, 1950, Serial No. 171,623

1 Claim. (Cl. 254—190)

This invention relates to sewer cleaning apparatus and, more particularly, to a jack leg pulley adapted for arrangement within the flush tank of a sewage system.

It is an object of this invention to provide a jack leg pulley of simple construction and of a rigid portable design.

A further object of this invention resides in the provision of a jack leg pulley which is adapted to be fixedly secured within a flush tank of a sewage system to permit guiding of a cable through the sewer from the drum of a winch disposed at ground level above the flush tank.

In the drawings:

Fig. 1 is a side view of the jack leg pulley of this invention.

Fig. 2 is a view of the jack leg pulley taken at right angles to Fig. 1.

Fig. 3 is a diagrammatic sectional view of a sewage system including a flush tank and a manhole and illustrating the mode of use of the jack leg pulley of this invention.

Fig. 4 is a vertical section through the flush tank illustrated in Fig. 3.

Fig. 5 is a horizontal section through the flush tank illustrated in Fig. 3.

The jack leg pulley of this invention is particularly adapted for cleaning the sewer crock extending between a manhole and a flush tank at the high end of the sewer line. In the drawings I have shown, for the purpose of illustration, a manhole generally referenced as 10, a flush tank 12 and a sewer crock 14 extending between and connecting the flush tank with the manhole. Flush tank 12 has a circular sidewall 16 providing an opening 18 at the upper end thereof. A steel pipe 20 projects into tank 12 adjacent the bottom thereof. The sewer crocks 14 extend from the outer end of pipe 20 to the inlet 22 of manhole 10. The inner end of pipe 20 is provided with a flange 24 on which a cover plate (not shown) may be secured.

As is conventional in flush tanks of this general construction, pipe 20 lies in a recess 26 at the bottom of the flush tank, the recess 26 providing a centrally disposed trench in the bottom wall 28 of the flush tank so that the pipe 20 is disposed below the level of the bottom wall of the tank. A trap 30 is connected with pipe 20 and extends at its upper end above the bottom wall 28 of tank 12. The open end of trap 30 is provided with a loosely fitting bell cap 32. A by-pass conduit 34 connects at one end with pipe 20 and at its other end the by-pass conduit 34 opens into flush tank 12 at a point spaced above the bottom wall 28 of the tank. A conduit 36 pro-

jects through the sidewall 16 and into flush tank 12 at a level spaced slightly above the inlet of by-pass conduit 34. Conduit 36 is connected with a source of water.

In a sewage arrangement of this type, the sewer lines are flushed periodically, for instance, every 24 hours. This is accomplished by admitting water into flush tank 12 through conduit 36. It will be appreciated that, with bell cap 32 seated on trap 30 and with the cover plate secured over flange 24 of pipe 20, the water level will rise in flush tank 12 until it reaches a level where the pressure of the water is sufficient to raise bell cap 32 off the end of trap 30 and thereby permit the water to rush through trap 30, pipe 20 and sewer crock 14 through the manhole 10 and then through the succeeding manholes along the lower end of the sewer line. By-pass conduit 34 is provided as a safety measure in case the bell cap 32 fails, for some reason or other, to function.

The periodic flushing of the sewer line as above described is conducive to the maintenance of unobstructed sewer lines. It infrequently happens, however, that an accumulation of silt and other matter in the sewer line seriously impairs the free flow of sewage, and it therefore becomes necessary to clean out the sewer lines 14 by a method more effective than simply flushing. The customary procedure is to clean these sewer lines by means of a bucket 38 or the like which is drawn through the sewer line from the manhole 10 to the flush tank 12 by means of a cable 40 which is operated by a suitable power winch 42 disposed at ground level over opening 18. This cleaning operation, of course, necessitates the removal of the cover plate from the flange 24 at the inner end of pipe 20 for the introduction of cable 40 through the end of pipe 20.

One of the difficulties invariably encountered in this method of cleaning sewers resides in the inability to properly guide the cable 40 through the sewer line from the flush tank end of the line. This difficulty results primarily from the fact that the pipe 20 is disposed within the trench 26 below the bottom wall 28 of the flush tank. The jack leg pulley of this invention is designed primarily for this purpose and, as is illustrated in Fig. 1, generally comprises a pair of telescoping tubular members 44 and 46. Tubular member 44 is provided with a plurality of longitudinally spaced openings 48 through which a bolt 50 may be inserted so that the members 44 and 46 can be arranged in a plurality of extended positions.

A pulley block 52 is fixed at one end of mem-

ber 44 as by a circumferential weld 54. Pulley block 52 comprises a generally rectangular frame 56 provided with a transversely extending pin 58 on which a pulley 60 is journaled for rotation. Spacers 62 are arranged on pin 58 between the sidewalls of pulley 60 and the sides of frame 56. Spacers 62 serve to maintain pulley 60 in alignment with the longitudinal axis of members 44 and 46. In other words, pulley 60 is centrally mounted with respect to the axis of members 44 and 46 so that, when a cable is guided through the pulley, the force thereof does not tend to tilt or twist the assembly.

Within the outer end of member 46 there is arranged a threaded shaft 64 on which is threadedly engaged a nut member 66 provided with opposed handles 68. The outer end 70 of shaft 64 is wedge shaped and terminates in a rather sharp point. Nut 66 bears against the outer end of tubular member 46; and the arrangement is such that, when the wedge shaped end 70 of shaft 64 is prevented from turning, the nut 66 may be turned in either one direction or the other by means of handles 68 to move shaft 64 axially inwardly or outwardly of tubular member 46.

A projecting member 72 is welded, or otherwise suitably secured, to the frame 56 of pulley block 52 at a point opposite the connection of tubular member 44 with the frame 56. The projecting member 72 terminates in a flat blade portion 74. Member 72 is secured to frame 56 such that the blade 74 is substantially perpendicular to the plane of pulley wheel 60. The wedge shaped portion 70 and the projecting member 72 form a pair of foot members at opposite ends of the assembly which enable rigidly supporting the assembly in a desired position within the flush tank 12.

The manner in which the jack leg pulley of this invention is arranged within the flush tank is best illustrated in Fig. 3. The assembly is positioned within the flush tank with the flat blade 74 of foot member 72 disposed against the corner formed by the bottom wall 76 of trench 28 in the sidewall 16 of the flush tank. In the opposite sidewall of the flush tank there is chiselled a small groove as at 78 in which the wedge shaped member 70 may be engaged. The assembly is inclined, as shown in Fig. 3, such that the bottom run of the pulley is aligned axially with pipe 20. Nut 66 is then turned in the proper direction to force the wedge portion 70 into groove 78 and thereby effectively lock the assembly in the inclined position illustrated. A conventional manhole pulley block 79 may be similarly arranged in the manhole 10.

When it is desired to clean the sewer crock 14 extending between manhole 10 and flush tank 12, a relatively light cable 80 is guided from manhole 10 through sewer pipe 14 to the flush tank 12. Cable 80 is guided around the pulley 19 in the manhole and through the pulley of the jack leg in the flush tank and is extended upwardly through the opening 18 of flush tank 12. Cable 80 is then connected with the end of cable 40, and the winch 42 at the manhole is then operated to wind up cable 80 and thereby pull cable 40 through the sewer and into the manhole. Cables 80 and 40 are provided at their free ends with connectors 84 which are preferably in the shape of a clevis which permits the ends of the cables to be readily connected or disconnected. It will be observed that sufficient clearance 86 is provided between each pulley and pulley block so that the cables, together with the clevis members 84, may

be passed therethrough. After the end of cable 40 is pulled through to manhole 10, the cables are disconnected and the bucket member 38 is connected between the cables. Bucket 38 has a bottom arranged as a pair of pivotal half sections 39 which close when the bucket is pulled in the direction of manhole 10 and which open when the bucket is pulled in the direction of flush tank 12. Winch 42 at flush tank 12 is operated to wind up cable 40 and thereby pull bucket 38 with its bottom sections 39 closed through sewer 14. The bucket 38 collects the silt and other accumulations in the sewer line 14.

It will thus be seen that the jack leg pulley of this invention is admirably suited for cleaning sewer lines. Its construction is such that it may be rigidly fixed within a flush tank or a manhole with the pulley aligned with the sewer line even though the sewer line enters the flush tank through a trench at the bottom of the tank. The pointed wedge shaped foot portion 70, together with the threaded shaft 64 and nut 66, enables locking of the assembly very rigidly in most any type of manhole or flush tank. At the same time, the flat blade portion 74 of the foot 72 prevents the pulley for tilting when the bucket 38 is pulled through the sewer line. The possibility of tilting of the assembly is further prevented by mounting the pulley 60 in alignment with the axis of member 44 and 46.

I claim:

A jack leg pulley comprising an extensible member, means for extending said extensible member to increase the effective length thereof, said extensible member having an elongate open frame fixed to one end thereof, a pulley wheel mounted in said open frame to rotate on an axis intersecting and perpendicular to the axis of said extensible member, the axis of said extensible member lying in the plane of said pulley wheel, said frame and pulley wheel providing an opening therebetween through which a cable engaging said pulley wheel may be extended, said frame having a foot member fixedly mounted thereon at the end thereof opposite the connection between said frame and said extensible member, said foot member extending generally axially of said extensible member and terminating at its free end in a blade having a straight edge which is perpendicular to the axis of said extensible member and generally parallel to the axis of rotation of said pulley wheel, a second foot member mounted at the other end of said extensible member, a threaded screw operatively associated with said last mentioned foot member, and a nut threaded on said screw and operatively associated with said extensible member so that when the nut is turned said last mentioned foot member is moved longitudinally of said extensible member, said last mentioned foot member terminating at its free end in a blade portion having a substantially straight edge which extends generally perpendicular to the axis of said extensible member.

ALLAN DE WOLF.
